UNITED STATES PATENT OFFICE.

EDWARD JORDAN, OF OTTAWA, ILLINOIS.

SLEIGH-RUNNER.

SPECIFICATION forming part of Letters Patent No. 352,092, dated November 2, 1886.

Application filed August 18, 1886. Serial No. 211,209. (No model.)

To all whom it may concern:

Be it known that I, EDWARD JORDAN, a citizen of the United States, residing at Ottawa, in the county of La Salle and State of Illinois, have invented certain new and useful Improvements in Sleigh-Runners; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of this invention, and is a side view. Fig. 2 is a cross-section through the runner, and shows a vertical section through the knee, as at *xx* on Fig. 1. Fig. 3 is a detail, and shows a cross-section of the knee at *yy* on Fig. 1. Figs. 4 and 5 are cross-sections through the channel-irons and T-irons. Fig. 6 is a modification; Fig. 7, a vertical section taken at *zz* on Fig. 6. Fig. 8 is a modification.

My invention relates to sleigh-runners; and it consists in the construction and novel combination of parts, as hereinafter described, and pointed out in the claims.

The object of the invention is to provide a runner for a bob-sled, sleigh, cutter, or hand-sled, from T-iron, steel, or other metal, and in constructing the braces of flat metal and channel-iron or other metal to give lightness and strength to the structure at the same time.

Referring by letter to the accompanying drawings, A designates the sled-runner, which is made of T-iron inverted and bent to the proper shape. The base of the runner A is provided with screw or bolt holes B, at suitable intervals, and immediately over each screw or bolt-hole B, the web C of the runner is slotted, as at D, for the reception of the nuts E, which are turned on the points of the screws F, which secure the soles G to the runners. The holes H in the soles G are countersunk around their lower ends, to receive the screw-heads H', and thereby present a smooth surface at the bottom of the sole.

The knees I² of the runners are composed 50 of the vertical channel-irons I, with the integral channel-iron arms I' at their upper ends, said arms I' extending outwardly and at right angles to the vertical knees I². Angular knee-braces J, also of channel-iron, 55 are bolted to the vertical knees I² through the upper ends of the vertical portions of said knee-braces J. The upper portions, K, of the angular knee-braces J extend inwardly along the tie-beams L, and are secured to the 60 lower edges of said tie-beams by screws or bolts M, passed up through the portions K into the tie-beams L. The tie-beams and the forward end of the runner are connected by a strip, N, secured to a rearwardly-extending 65 flange, P, at the front end of the runner. A-braces Q are secured at their lower ends by bolts Q' to the webs of the runners, and the upper ends of these A-braces are secured between the knees I and the knee-braces J by 70 R.

In some constructions, instead of connecting the knees and angular knee-braces rigidly to the under faces of the tie-beams L, I provide the knees and knee-braces at their upper ends with a half-round tie-bar, S, which is bolted thereto, and projects at each end slightly beyond the horizontal portions of the knees and knee-braces. I further provide two box-bearings, T, which are flanged on 80 their upper sides to fit the under face of the tie-beam L, bolts U U' being passed up through the box-bearings T and through the tie-beam, and secured in place by nuts V, screwed upon the slightly-projecting ends of 85 said screw-bolts U U'. In this construction only a single knee is used with each runner, and a single tie-beam only is required to connect them, and it allows either runner to oscillate over uneven ground without affecting 90 the position of the opposite runner.

Having described this invention, what I claim, and desire to secure by Letters Patent, is—

1. The combination, with the tie-beam and 95 T-metal runner, of the channel knee and channel knee-brace, connected at their upper ends by the half-round bar having projecting ends,

and the metal open boxes with closed outer ends secured to the tie-beam by screw-bolts, substantially as specified.

2. In a sleigh, the combination, with the tie-bar and runners formed of T-iron, of the channel-metal knees, the knee-braces secured at one end to the vertical flange of the T-irons, and their opposite ends secured to the

inner sides of the knees, as shown and described.

In testimony whereof I affix my signature in presence of two witnesses.

EDWARD JORDAN.
